UNITED STATES PATENT OFFICE.

FRANK J. WOOD, OF BROOKLYN, NEW YORK.

STEAM-ENGINE CYCLE.

Application filed December 27, 1917, Serial No. 209,120. Renewed December 21, 1920. Serial No. 432,370.

To all whom it may concern:

Be it known that I, FRANK J. WOOD, a citizen of the United States, residing at No. 153 Joralemon St., Brooklyn Borough, city of New York, and State of New York, have invented new and useful Improvements in a Steam-Engine Cycle, of which the following is a specification:

The object of my invention is to provide a method of using steam in the generation of power, that will convert into mechanical energy more of the heat that is contained in steam than is practicable in the ordinary steam engine cycle and by the method of working herein described I can utilize much of the latent heat that ordinarily escapes through the exhaust pipe. The action of the ordinary form of steam engine in which steam is introduced into each end of a cylinder at the commencement of the stroke of the piston, and is "cut off" later on in the stroke and then exerts more or less of a pressure to the end of the stroke is too well known to describe fully in detail, so when I refer to certain actions that take place in ordinary forms of steam engines I consider that it is unnecessary to explain fully every movement of the parts of the whole engine.

It is well known that during the stroke of the piston of an ordinary steam engine, after "cutting off" takes place the steam expands and throughout the remainder of the stroke the pressure and temperature generally reduces. It is also well known that if compressed air at the same pressure could, with the same "cut off" be used to actuate the same steam engine, after "cutting off" the pressure and temperature would reduce more in proportion than when steam is used. For instance, if the "cutting off" takes place when the steam pressure is 35 lbs. and 280 degrees temperature, and the piston advances until the steam expands to atmospheric pressure, then the temperature will be 212 degrees; while if air is used and at the point of cut off the pressure is 35 lbs., and the temperature has been raised to 280 degrees, then if the piston advances until the pressure is reduced to atmospheric, the temperature of the expanded air will be about 60 degrees.

It is well known that saturated steam during expansion after "cutting off" will partially condense into fine particles of water which for a short time remain suspended in the gaseous steam in the form of a mist. If

this steam with its suspended particles of water could be exhausted from the cylinder into a large tank and be brought to a comparatively motionless state therein, these particles of water will settle to the bottom.

As there is always an evolution of heat when steam changes to water, mostly for this reason the temperature of steam is higher at the end of the stroke than air is when expanded from the same initial pressure. The steam that condenses and enters into the formation of these particles of water gives up its latent heat to the enveloping gas as the particles of water are formed during expansion.

Now air alone in expanding in a steam engine cylinder does not partially condense into liquid particles in the same way that steam does, consequently, there being no stored up latent heat to draw upon the air must cool to a lower temperature. This cooling effect that air has during expansion, would, in a mixture of air and steam expanding in an engine cylinder, cause a larger proportion of the steam to condense than if steam were used alone; and it is obvious that the larger the proportion of air the greater the proportion of steam that will be condensed.

The condensing of the steam in the mixture being brought about to a large extent by the tendency of the air to reduce in temperature while expanding, it is obvious that the air must receive some of the latent heat given up by this condensing steam. It follows then that nearly all of the steam in the steam and air mixture can be condensed if the proper proportions of steam and air are mixed at a certain temperature and then expanded a sufficient number of volumes to bring the mixture to a temperature that is considerably below the boiling point of water under the pressure to which the expansion is brought. Now if the air in this mixture receives this latent heat it must necessarily be expanded in volume or raised in pressure over and above the volume or pressure that would prevail if air were used alone.

Raising the temperature with this latent heat means that more work can be put out by the piston from the same steam and such being the case it is obvious that an engine working a mixture made up of the right proportion of air and steam would be capable of converting a very large proportion of the latent heat of the steam into work.

To avoid a possible waste of latent heat it is practically necessary to exhaust in a closed chamber and draw from this chamber the same air over and over again for mixing 5 with the steam. The conditions in the chamber can be arranged so that the air can be at all times a near approach to 100 per cent humidity, while the air of the outside atmosphere varies greatly. If air much below 10 100 per cent humidity be drawn into the cylinder and mixed with steam, much latent heat would get away in the exhaust in the form of uncondensed vapor mixed with the air, as the exhaust air can never be below 15 the maximum humidity. The latent heat value of the uncondensed vapor in the air is too much to be wasted when it is considered that under normal conditions the volume of air that is used in the cylinder 20 is many times that of the steam. To get good efficiency the working cycle would be one that contemplates taking a certain volume of air at practically 100 per cent humidity, compressing the same to a certain 25 pressure and temperature, then mixing a smaller volume of steam at about the same temperature and pressure, then during a working stroke expanding the mixture to a pressure and temperature that will convert 30 the steam to water more or less suspended in air, then separating the particles of water from the air, but leaving the air at about 100 per cent humidity, then using this air again as above described.

35 I am enabled to obtain these results by means of the engine described below and illustrated by the accompanying drawings in which Fig. 1, shows the engine and all of the main features more or less diagrammatically. Fig. 2, shows the pressure curves indicating approximately the pressure changes that occur during the stroke of the piston. Pressures and temperatures are indicated by distances from the base line 50, 40 50, and distances along or parallel with the base line indicate stroke of piston. Points along the curves indicate pressures and temperatures at certain points in the stroke. In Fig. 1, the cylinder, 1, is mounted on a 55 frame of the type that is not unusual in vertical engines. An elongated piston, 2, having a length nearly equal to the stroke is connected by a piston rod, 3, to the usual cross-head, connecting rod, crank shaft and fly-wheel. A suitable governor, 4', of any well known type which can control the stroke and "cut off" of the slide valves, 4 and 5, by shifting the throw of the eccentric 6, can be used. The exhaust port, 7, is so 60 placed that the piston acts as the exhaust valve. This exhaust port communicates with the settling chamber, 8, through the pipe, 8'. There are two valves, 9 and 10, which open inwardly into the cylinder and 65 which permits of a flow of air from the ac-

cumulating reservoir, 17, through the pipes, 11 and 12, into the ends of the cylinder, 1. The valves are prevented from being closed until the proper time by the valve motion, 13, 14, 15, and the eccentric 16. The settling chamber, 8, is of such capacity that it will receive the exhaust flow from the engine and slowly carry it to the outlet, 18, with such a very slight amount of current that any liquid particles that may be suspended in the air mixture will tend to settle. The deflecting baffle, 19, and the porous screen, 24, tend to project the liquid particles downwardly and then collect them after they issue from the exhaust pipe, 8'. A pump, 21, draws off the accumulation of water from the settling chamber, 8, and is used also to maintain a certain vacuum in this chamber. This pump, 21, is of such capacity that it will pump all of the water 75 of condensation and just sufficient air to equal the leakage and that which is brought in mixed with the steam and bring about a certain desired vacuum. A pump, 22, is arranged so that it will draw practically 80 all of the air portion of the mixture that issues from the exhaust pipe, 8', into the chamber, 8, and slightly compress it into the accumulating reservoir, 17. The two pipes 85 11 and 12 afford communication between the accumulating reservoir, 17 and the two check valves, 9 and 10. As occasionally an abnormal influx of steam may occur, and it is necessary to keep the chamber, 8, at a constant and a comparatively low temperature, I insulate the shell of this chamber 90 with a suitable thickness of any well known heat insulating material and to maintain the temperature at a comparatively low degree. I provide the cooling coil, 23, through 95 which flows a cold solution that is cooled by means that will produce a certain sufficiently low temperature. A pump, 24', discharges any water that might accumulate in reservoir, 17.

100 There are comparatively large clearance spaces, 30, 31, at the ends of the cylinder, 1, in order that there will be room for the air that is compressed to a moderate pressure during the compression stroke of the piston. The steam ports, 32, 33, are somewhat contracted at the openings into clearance spaces 30, 31, in order that the steam will 105 flow into the clearance spaces with some velocity and have a jet action that will thoroughly mix the inflowing steam with the compressed air. The steam that flows through the ports, 32, 33, comes from the steam chest, 34, which receives steam from a suitable source of steam supply through 110 the pipe 35.

115 In describing the operation it is unnecessary to describe in detail the method of getting the engine up to the proper speed or getting of proper vacuum to the chamber 120 125 130

8, or the slight pressure in reservoir, 17, for it is obvious that with the steam valves and pumping attachments shown that pressure could be applied to the piston, a partial 5 vacuum could be pumped in the chamber, 8, and a slight pressure over that of this partial vacuum could be pumped into the reservoir, 17, so that it is obvious that the engine could be started and be brought up to 10 a suitable speed. Assuming that the engine is running at normal speed and at the instant that the piston is at the lower extreme of its stroke, air at 35 lbs. pressure and 280 degrees temperature has been compressed by 15 the piston, 1, into clearance space, 31. The valve, 5, over the port, 33, now opens and as the steam in the steam chest is at a pressure slightly above 35 lbs. it blows into the cylinder through the contracted opening of 20 the port 33, with such a velocity that the inflowing steam mixes intimately with the compressed air. The piston now moves upward and the steam valve over the port 33, remains open until the "cutting off" point 25 in the stroke of the piston is reached. While the steam flows into the cylinder up to the "cutting off" point, the pressure in the cylinder is maintained approximately at 35 lbs. After "cutting off" expansion takes place 30 and the pressure and temperature gradually lowers, the lowering temperature condenses more and more of the steam into a mist until the end of the stroke is reached then the piston uncovers the exhaust port, 7, and the 35 air, mist and remaining steam is free to flow through the pipe 8'. As there has been pumped a slight pressure in reservoir, 17, over that in the chamber, 8, this pressure is sufficient to open the check valve, 10, and 40 the air that now flows freely into the cylinder, flushes air, mist and steam out through the exhaust port, 7, into the settling chamber, 8. The displacing humid air that fills the cylinder when the exhaust port 45 is again covered by the piston on the return stroke is for a short time prevented from compressing by the valve, 10, being held open by the valve motion and eccentric, 13, 14, 15 and 16. This valve motion is so timed 50 in its action that the valve, 10, is seated when the piston arrives at the certain point in its stroke that the compression at the end will be approximately 35 lbs. The temperature should be approximately 280 degrees 55 when the compression is completed and this temperature is obtained more by compressing but depends to a certain extent on the temperature of the air at the moment compressing commences; this commencing of 60 compression temperature is more or less controlled by maintaining a certain temperature in the chamber, 8, by means of the cooling coil, 23. At the moment that the mixture of air, mist and possibly steam issues from the 65 exhaust pipe 8', into the chamber 8, the

mixture is deflected downward by the baffle, 19, and then through the perforated or porous screen, 24, in order that the particles of water may be brought towards the bottom and together. The volume of this settling chamber being greatly larger than the volume of the cylinder of the engine, there is not sufficient current to carry the particles of water up with the air so the air is drawn into the pump, 22, in a state that is of maximum humidity but comparatively free of mist and is slightly compressed as it is stored in the reservoir, 17.

The engine as shown being double acting, the action in both ends of the cylinder will be the same.

The point, 51, on the indicator diagrams or curves shown in Fig. 2, indicates the compression pressure of 35 lbs. of air in the cylinder at the commencement of the stroke 85 of the piston. The line, 51 to 52, indicates the pressure during the time that steam is flowing from the steam chest into the cylinder. The point, 52, is the "cutting off" point. The line 52 to 53 indicates the reducing of the pressure during the expansion 90 of the mixture of air and steam. The line 53 to 54 and to 55 indicates the pressure conditions during the time that the piston has uncovered the exhaust port and the air, 95 mist and possibly some steam is flowing into the settling chamber. The line 55 to 56 indicates the pressure during the time the valve, 10, is being held open by the valve motion 13, 14, 15, 16. The line 56 to 51 indicates the pressure during the compressing 100 of the air.

Now if air alone should be used, the expansion after "cutting off" would roughly approximate the pressures indicated by the 105 line, 52 to 57, and if steam alone should be used the pressures during expansion would approximate those shown by line, 52 to 58.

Although I could use an initial pressure of 35 lbs. and expand to atmospheric pressure and the engine would work within the scope of this invention yet I prefer to have the expansion go further than to atmospheric pressure for it is obvious that the greater the volume of expansion the lower 110 the temperature at the end of the stroke of the piston which means that more of the steam will be condensed by the expanding of the mixture of air and steam with a given ratio of air to steam at a commencing pressure of 35 lbs., and consequently more of the heat will be converted into work with a smaller amount of air.

Assuming that the expansion line 52 to 125 58 indicates that steam has expanded from 35 lbs. to 20 inches of vacuum then the temperature would fall from about 280 to about 162 degrees. Air in expanding through the same range of pressure would fall in temperature as indicated by the line, 52 to 57, 130

from 280 degrees to a temperature that is far below that of steam notwithstanding the fact that considerable heat would be transferred from the cylinder walls to the air 5 within. For the reason that there would be considerable transferring of heat from the compressed air and steam to the cylinder walls during the first part of the stroke and later on in the stroke from cylinder walls 10 to the air and the remaining steam it would be practically impossible to plot curves that would be accurate indications of the pressures during expansion, consequently I do not intend that the indicating curves shown 15 in Fig. 2, be considered as being any more than rough approximations of the pressures that are obtained in the cylinder.

If much "mist" should be returned to the cylinder much of the heat of compression 20 would be absorbed by this mist being re-evaporated so that loss of efficiency would result.

I use an initial steam pressure on the cylinder that approximates 35 lbs. and 280 degrees temperature in the above description 25 of my invention although I do not confine myself to this one pressure. Pressures both higher and lower could be employed to advantage in some cases.

30 A governor, 4', connected to the steam valve operating motion can control the point of "cut off" of the steam valves, 4 and 5, so that the "cutting off" point, 52 will be nearer to or farther away from the point, 35 51. In other words the steam will follow the piston for a shorter or a longer distance in its stroke depending on the power requirements. When the point of "cut off" is shifted the expansion pressure must necessarily 40 change so that the line, 52 to 53 will be below or above the position shown in the diagram. Obviously there would be more heat get into the settling chamber, 8, when the point of "cut off" is farther from point 51, but in 45 order that the air will always be brought to approximately the same temperature in the chamber, 8, I employ the cooling coil, 23, through which flows a cooling agent having the cooling capacity that will bring the air 50 in the chamber 8, to the temperature desired.

As the temperature in the chamber, 8, can only reduce and never raise by the action 55 of the cooling coil, 23, it is obvious that the air in this chamber, 8, cannot be at any other than maximum humidity. The slight pressure that is applied in order to compress this air and force it into the reservoir, 17, would change the relative humidity in this reservoir, but when the pressure is relieved by 60 the air flowing into the cylinder during flushing, the pressure will lower again and the humidity will obviously return to the maximum.

I do not consider that my claims refer to 65 this invention as applied only to a recipro-

cating engine in the working cycle herein claimed. Any kind of an engine that can be operated by the steam and air mixture working under approximately the conditions above described I consider as being covered 70 by my claims which are:

1. A steam engine working cycle, which, commences with the displacing of the exhaust volume by the flowing of a charge of air of approximately 100 per cent humidity 75 into an engine cylinder at the finish of a working stroke; then compressing into the clearance space between the piston and the end of the cylinder the said air to a certain pressure and temperature; then mixing in this compressed air steam having approximately the same temperature and pressure; then flowing in steam to the "cutting off" point of the stroke and then expanding until all or the greater part of the steam of the mixture 80 is condensed into a mist; then flushing the mixture of air and mist from the cylinder into a separating chamber; then separating the mist from the air in said chamber and withdrawing the collected water; then cooling the air to a desired temperature but maintaining a humidity of 100 per cent; then forcing the said air at a slight pressure 85 into a reservoir; then with said air displacing the exhaust and charging the cylinder 90 at the end of a subsequent working stroke of the piston.

2. A steam engine working cycle, which, commencing at the finish of a working stroke of the piston the exhaust volume in 100 the cylinder is displaced by the flowing of a charge of air of approximately 100 per cent humidity into the engine cylinder then with the piston compressing into the clearance space, the said air to a certain pressure and temperature; then mixing into this compressed air, steam having approximately the same temperature and pressure; then flowing in steam to the "cutting off" point of the stroke and expanding until all or the greater part of the steam of the mixture is 105 condensed into a mist; then flushing the mixture of air and mist from the cylinder into a separating chamber; then separating in said chamber the mist from said air; then cooling said air but maintaining the humidity at 100 per cent; then accumulating said air into a reservoir for displacing the exhaust of and charging the cylinder at the 110 commencement of a subsequent cycle.

3. A step in a steam engine working cycle, the displacing of the exhaust volume by the flowing of air of approximately 100 per cent humidity into an engine cylinder, then with the piston, compressing into the clearance space the said air to a certain pressure and temperature, then mixing in this compressed air steam having approximately the same temperature and pressure; then flowing in steam to "cutting off" point of the stroke and 125 130

expanding until the greater part of the steam of the mixture in the cylinder is condensed into a mist, then separating the mist from the air and returning the same air to the 5 same cylinder for a subsequent cycle.

4. In a steam engine working cycle, the displacing of the exhaust volume by the flowing of a charge of air of approximately 100 per cent humidity into an engine cylinder, then with the piston compressing into 10 the clearance space the said air to a certain pressure and temperature then mixing in this compressed air steam having approximately 15 the same temperature and pressure, then flowing in steam to the "cutting off" point of the stroke and expanding until

practically all or greater part of the steam of the mixture in the cylinder is condensed into a mist, then flushing the mixture of air and mist from the cylinder into a separating 20 chamber by using a displacing charge of air at approximately 100 per cent humidity, said displacing charge of air having been previously passed into and through said separating chamber and said displacing 25 charge of air having been brought to a certain pressure or vacuum in said separating chamber.
